UNITED STATES PATENT OFFICE.

STANISLAW MACKIEWICZ, OF KOKOMO, COLORADO.

BULLET.

1,203,653.

Specification of Letters Patent. Patented Feb. 4, 1919.

Application filed November 9, 1918. Serial No. 261,828.

To all whom it may concern:

Be it known that I, STANISLAW MACKIEWICZ, a citizen of the United States, residing at Kokomo, in the county of Summit and State of Colorado, have invented certain new and useful Improvements in Bullets, of which the following is a specification.

This invention relates to projectiles and more particularly to an improved construction for projectiles designed to lengthen the trajectory of the missile.

The primary object of the invention is to provide a projectile having incorporated therein a series of rockets, designed to give additional impetus to the missile so that it will be carried a greater distance than would be possible to obtain from the initial impulse.

The invention further aims to improve the construction of the projectile so that it will more readily cut through the air and thereby lessen the resistance offered by the air to the missile when in flight.

The above and additional objects are accomplished by such means as are illustrated in the preferred embodiment and in the accompanying drawings, wherein like characters of reference denote like or corresponding parts throughout the several views, in which:

Figure 1 is a longitudinal section partly in elevation of the projectile constructed in accordance with my invention.

Fig. 2 is an end elevation of the same, and

Fig. 3 is a transverse section taken on the line 3-3 of Fig. 1.

Referring to the drawings, wherein is illustrated the preferred form of my invention, and in which like numerals of reference indicate corresponding parts throughout the several views the outer casing 1 is constructed of the usual metallic material and is of cylindrical formation at one end and gradually tapers, by virtue of the provision of a conical end 2, to a pointed end 3 which receives the usual cap designed to cause the explosion of the missile when it strikes an object. The tapered conical portion 2 is considerably longer than the cylindrical portion 1 and the gradual taper of the pointed end thus provided, will materially assist in lessening the resistance offered by the air when the missile is in flight.

The usual charge of explosive material is

placed within the casing and one end of the cylindrical portion 1 is closed by the end wall 4. This end wall is provided, as shown to advantage in Fig. 2, with a plurality of openings 5 each of which communicates with one of the tubes 6 arranged within the casing. Any number of the tubes 6 may be provided, but in the present instance, three are shown arranged in equally spaced relation and extending longitudinally through the casing and converging toward the pointed end of the casing at which point they are joined together. These tubes are filled with a suitable combustible charge which, when ignited, creates the gases which as they escape through the openings 5, drive the projectile forwardly at a greater speed and thereby lengthen the trajectory. Therefore, with this construction, it is possible to project a missile a predetermined distance, with less initial impulse than would ordinarily be employed.

The foregoing description and accompanying drawings have reference to what might be considered to be the preferred or approved form of my invention. I desire it to be understood, that I may make such changes in the construction, combination and arrangement of parts, materials, dimensions, et cetera as may prove expedient and fall within the scope of the appended claims.

Having thus fully described my invention, what I claim as new and desire to secure by Letters Patent, is:—

1. A missile of the character described comprising a casing having an interior charge of explosive material, and provided on its interior with a plurality of longitudinally extending rockets having open communication with one end of the missile.

2. A missile of the character described comprising a casing having an elongated tapered point and provided on its interior with an explosive charge, a plurality of rockets comprising tubes arranged within the casing and extending longitudinally through the said explosive charge and having open communication with the blunt end of the missile.

3. A projectile of the character described comprising a casing having an elongated tapered point at one end, and a closed wall at its opposite end, the latter being provided with a plurality of openings, the said casing

containing an explosive charge, a plurality of tubular members provided within the explosive charge and extending longitudinally through the said casing and having their forward ends converged toward each other to meet within the said pointed end of the missile, the opposite ends of the said tubes being in communication with the openings

in the end walls, and a combustible charge arranged within each of the said tubes. 10

In testimony whereof I affix my signature in presence of two witnesses.

STANISLAW MACKIEWICZ.
